UNITED STATES PATENT OFFICE.

FRANK C. REMSBERG, OF SANTA ANA, CALIFORNIA.

GLASS-CUTTING FRAME.

1,357,474.

Specification of Letters Patent. Patented Nov. 2, 1920.

Application filed February 24, 1919. Serial No. 278,756.

To all whom it may concern:

Be it known that I, FRANK C. REMSBERG, a citizen of the United States, residing at Santa Ana, in the county of Orange and 5 State of California, have invented new and useful Improvements in Glass-Cutting Frames, of which the following is a specification.

It is common practice among glaziers to 10 use a table covered with a fabric, and having scales on the left hand and lower edges, for the support of glass panes, when cutting the latter. My invention relates to a frame serving as a table for like purposes.

15 It is an object of this invention to provide an open spaced frame, which will serve as a means for setting and alining the straight edge for guiding the glass cutter and the glass panes to be cut. Another 20 object of this invention is to provide a frame of the character described with adjustable stops of a novel character adapted for abutment by the pane or straight edge.

25 In addition to the broader features of this invention, there are certain details of construction, whereby a simple, convenient frame, light in weight is obtained, and whereby a structure having a certain amount 30 of resiliency and flexibility so as to conform to the surface of a glass pane, may be secured.

I accomplish the above mentioned objects 35 by means of the embodiment of my invention illustrated in the accompanying drawing, in which:

Figure 1 is a plan view of a complete frame with two adjustable stops thereon and the straight edge disposed upon the frame, some of the scale markings being 40 omitted. Fig. 2 is a bottom view of the straight edge drawn to a reduced scale. Fig. 3 is an end view on an enlarged scale 45 of the straight edge. Fig. 4 is an elevation on an enlarged scale of the bottom right hand border piece of the frame with one of my adjustable stops mounted thereon. Fig. 5 is a section taken on the line 5—5 of 50 Fig. 4. Fig. 6 is a detail view of the foldable stop mounted on a side border piece. Fig. 7 is a fragmentary plan view on an 55 enlarged scale illustrating the bottom right hand corner of the table.

The table is of a general checker board form having border pieces 8, 9, 10 and 11. 55 The top and bottom border pieces 8 and 10 are marked with scales reading from

left to right and divided according to some standard unit of measurement, inches for illustration. The side border pieces, 9 and 11 are similarly marked with scales reading 60 from the bottom to the top. Bridging the side pieces are slats 12 spaced at uniform intervals. The upper surfaces of the slats are in the same plane as the upper surfaces of the side pieces. Bridging the top and 65 bottom border pieces are slats 13, which are uniformly spaced and have their upper surfaces in the same common plane. All of the slats 12 are marked with scales corresponding to the scales on the top and bottom border pieces. In a like manner, all of 70 the slats 13 are marked with scales corresponding to the scales on the side border pieces. The slats 12 and 13 are notched to receive each other at their intersections to 75 provide a flat upper surface upon which the glass may be laid. This construction provides a frame which under pressure can be somewhat warped so that a glass pane laid thereon will not bend and warp under 80 pressure, but rather the frame will bend to conform to the surface of the glass, and thereby prevent cracking of the latter.

Upon the side border pieces of the frame 85 are foldable stops indicated by 14 and 15. These stops are located adjacent the bottom border piece and are duplicates of each other. One will be described. Referring particularly to Figs. 4 and 6, a butt bracket 16 has pivoted therein an arm 17, so that 90 when folded, as shown in dotted lines, the arm will be below the upper surface of the frame, and when opened the arm will extend above the upper surface of the frame and be held against movement in one direction to the right in Fig. 6 (further opening movement) by the arm throwing against the back of the bracket 16.

Referring particularly to Fig. 1, adjustable stops are indicated by 18. There are 100 two shown herein, but several may be used as found convenient, and as they are duplicates of each other, only one will be described. Referring particularly to Figs. 4 and 5, a stop is comprised of a slide block 105 19. A notch 20 is cut upon the lower face of the slide block for the reception of a bolt 21, so that the latter will clear the surface upon which the block rests. On the upper surface of the block adjacent the 110 edges are grooves 22 and 23, in which are hooked clamps 24 and 25. The bolt 21 ex-

tends through alined holes in the clamps 24 and 25. Upon the threaded end of the bolt is a thumb nut 26. When the adjustable stop is disposed upon one of the border 5 pieces or slats, and the thumb nut loosened, the slide block may be adjusted to extend more to one side than the other of the clamps, as desired. By tightening the thumb nut 26 the stop is clamped to the 10 border piece or slat, and the slide block is clamped in fixed position with respect to the clamp.

The straight edge is of the usual form, but provided with a bracket 28. This bracket is 15 intended to be hooked over the outside edge of a border piece and is convenient in locating and holding one end of the straight edge in its proper position while the other end is being located and held. For instance, the 20 operator hooks the bracket 28 over the edge of the frame farthest from him and thus can hold that far end of the straight edge in fixed position while he locates the end he holds in his hand. The stops 14 and 15 are 25 so positioned that when opened and the straight edge abuts thereagainst, the lower edge of the straight edge will be disposed above the lower edge of the frame a distance equal to that which the cutter will extend 30 beyond the straight edge. By moving the cutter along the straight edge in this position, a cut will be made which coincides with the lower edge of the frame. (I mean by the "lower edge" the edge normally closest to 35 the workman and which, in the drawings, is the edge 10.)

Suppose a pane of glass is to be cut of the dimensions, say, 12 x 24 inches, and that the stock is rectangular; adjustable stops 18 40 are placed as shown in Fig. 1 with the lower faces of the slide blocks registering with the marks on the slat and side piece numbered 12. The stops 14 and 15 are then raised to the position shown in Fig. 6. The 45 upper edge of the stock pane is butted against the stops 18 and the left hand edge against the stop 14. The straight edge is then placed below stops 14 and 15 so that it butts against the latter, and the cutter 50 drawn along the lower edge of the straight edge, thereby making a cut 12 inches from the upper edge of the pane. The straight edge is then lifted and the bracket end hooked over the top piece with the right 55 hand edge disposed about in registry with the mark 24 on the top piece. However, enough clearance is left between the mark and the right hand edge of the straight edge to compensate for the clearance of the cutter. The friction of the bracket 28 against 60 the top piece will prevent the straight edge from becoming displaced from its position at the top of the frame. The bottom end of the straight edge is then swung into a position 65 on the bottom piece corresponding to its

position on the top piece. Another cut is then made at right angles to the first cut, and 24 inches from the left hand edge of the pane. If a number of the panes are to be 70 cut of the same size, then more of the adjustable stops may be placed upon the slats 12 in proper position for the straight edge to abut against them with the cutter edge in position for the dimensions to be cut. In trimming edges, it will be found convenient 75 to move the slide block of the adjustable stop so that the thumb nut will clear the edge of the stock. Again, when the clamps are to be attached close to slats at right angles, the slide block may be moved in the 80 clamp to dispose its end at the proper position. There are various other uses for the adjustable blocks which will be apparent to a glazier making use of the frame; but these uses are so numerous in detail, that it is 85 superfluous for me to attempt to describe them here.

Having described a preferred form of my invention, what I claim is:

1. A glass cutting frame comprised of 90 oblong pieces arranged in a plane, additional pieces crossing the first mentioned pieces and secured thereto, said pieces forming a substantially quadrilateral, lattice-like frame, and stops foldably mounted on the frame adjacent an edge of said frame for abutment by a straight edge.

2. A glass cutting frame comprised of oblong pieces arranged in a plane, additional pieces crossing the first mentioned pieces and 100 secured thereto, said pieces forming a substantially quadrilateral, lattice-like frame, stops foldably mounted on the frame adjacent an edge of said frame for abutment by a straight edge, and adjustable stops on said 105 cross pieces.

3. A glass cutting frame, embodying oblong pieces arranged in lattice form and with their upper surfaces in a common plane, and an adjustable stop embodying a 110 block, and clamping members adapted to clamp the block and also clamp the cross pieces, and the block itself being movable with relation to the clamping members.

4. A glass cutting frame, embodying two 115 sets of parallel oblong pieces arranged in a plane, additional pieces crossing the first mentioned pieces and secured thereto, said pieces forming a substantially quadrilateral, lattice-like frame and with their upper surfaces in a common plane to provide a glass supporting surface; the frame thus formed 120 being somewhat flexible in directions transverse to said plane; and each cross piece of each set being scaled from one edge of 125 the frame.

5. A glass cutting frame, embodying two sets of parallel oblong pieces arranged in a plane, additional pieces crossing the first mentioned pieces and secured thereto, said 130

pieces forming a substantially quadrilateral, lattice-like frame, the pieces of the two sets crossing each other at right angles and having their upper surfaces in a common plane 5 to provide glass supporting surface; each cross piece of each set being sealed from one edge of the frame; and adjustable stops on the cross pieces.

6. A glass cutting frame, embodying two 10 sets of parallel oblong pieces arranged in lattice form, the pieces of the two sets crossing each other at right angles and having their upper surfaces in a common plane to provide a glass supporting surface; each

cross piece of each set being sealed from one 15 edge of the frame; and adjustable stops on the cross pieces, said stops embodying a block and clamping members adapted to clamp a cross piece at its opposite sides and the block being longitudinally adjustable 20 with reference to the clamping members.

In witness that I claim the foregoing I have hereunto subscribed my name this 18th day of February, 1919.

FRANK C. REMSBERG.

Witness:

VIRGINIA BERINGER.
